UNITED STATES PATENT OFFICE.

GEORGE W. REAM, OF CANTON, OHIO, ASSIGNOR TO THE BUCHER & GIBBS PLOW COMPANY, OF SAME PLACE.

DESIGN FOR A HARROW-FRAME.

SPECIFICATION forming part of Design No. 29,711, dated November 22, 1898.

Application filed October 28, 1898. Serial No. 694,842. Term of patent 14 years.

To all whom it may concern:

Be it known that I, GEORGE W. REAM, a citizen of the United States, residing at Canton, in Stark county, and State of Ohio, have invented and produced a new and original Design for a Harrow-Frame, of which the following is a specification.

The design is illustrated in the accompanying drawings, in which—

10 Figure 1 is a plan view of the frame. Fig. 2 is a side elevation looking from the left of Fig. 1. Fig. 3 is a front elevation, and Fig. 4 is a view looking from the right of Fig. 1.

15 The leading features of the design comprise, first, the harrow-frame proper in its configuration or outline, and, secondly, the form of the shoe and its supporting-bracket. As shown particularly in Fig. 1, the frame of the harrow has a straight side A, with its front end curved,

as at B, and the side opposite to A, as at C, is composed of two straight portions $a a'$ and two inclined portions $b b'$, this making what may be termed a "stepped side." The sides A C are connected by cross-bars D. The supporting-shoe E has a straight bottom portion d with a curved front portion e , and the shoe is made concave on its upper face, as shown at f in Fig. 1. A curved bracket g extends from the concave bottom of the shoe to the frame proper. 30

What I claim is—

The design for a harrow-frame as herein shown and described.

GEORGE W. REAM.
